J. Kaplan

Attorney

UNITED STATES PATENT OFFICE.

WILLIAM BLUMENTHAL, OF PHILADELPHIA, PENNSYLVANIA.

COAT SHIELD.

Application filed December 4, 1926. Serial No. 152,624.

This invention relates to coats and more particularly to shields to protect the inside portion of the coat lying below the arm hole, and is adapted especially to coats whose 5 lining does not extend throughout the entire area of the coat.

The principal object of the invention is the provision of a shield of substantially the same material as the body of the coat sewed 10 in place underneath the arm hole, which will act as a finish to the lining and at the same time prevent wear and tear of the lower portion of the arm hole and the inside of the coat, and thus give the coat a 15 longer life.

Other objects will appear as the disclosure progresses. The drawings are intended merely to indicate a possible embodiment of the invention. It is obvious that the actual 20 needs of manufacture may necessitate certain changes. It is therefore not intended to limit the invention to the embodiment illustrated, but rather to define such limits in the appended claim.

For a more detailed understanding of the invention attention is called to the drawings in which

Figure 1 is an inside view of one half of a coat showing the shield sewed in place. The 30 other half being a duplicate of that shown.

Figure 2 is a section on line 2—2 of Figure 1.

Referring now to the drawings in which like reference characters denote like parts 35 throughout the specification, numeral 1 designates the coat, 2 the arm hole, 3 the coat

lining and 3^b the coat pocket. Between the lining and the body of the coat at the front, is provided the usual buckram 4.

Underneath the arm hole and sewed to 40 the edge of the lining 3 at 3^a is the shield 5 composed of a narrow strip of cloth 6 having a widened portion 7 at the top where it reaches the arm hole and provided with binding 8 to give the shield a neat appear- 45

The shield is preferably made of a heavier material than the lining in order to keep the garment in shape and to take up the wear and tear at that portion of the coat. 50

It will thus be seen that I have provided a shield which will protect the garment from wear and tear around and below the arm pits, which will give a finish to the lining and which will add to the life of the garment. 55

Having thus described my invention, what I desire to secure by United States Letters Patent is:

The combination with a coat, of a shield 60 attached to the inside thereof underneath the arm pit, an outside pocket, said shield composed of a straight portion reaching downward substantially on the level with the outside pocket, a widened portion at 65 the top where it reaches the arm pit, one side of said shield sewed to the coat lining and the other side sewed to the body of the coat and a strip of binding sewed to the shield for reenforcing the edges. 70

In testimony whereof I affix my signature.

WILLIAM BLUMENTHAL.
